UNITED STATES PATENT OFFICE.

HENRY POCOCK, OF LONDON, ONTARIO, CANADA.

MOLDING-MACHINE.

No. 873,598.

Specification of Letters Patent.

Patented Dec. 10, 1907.

Application filed October 18, 1906. Serial No. 339,505.

To all whom it may concern:

Be it known that I, HENRY Pocock, of the city of London, in the county of Middlesex, Province of Ontario, in the Dominion of Canada, have invented certain new and useful Improvements in Molding-Machines; and I do hereby declare that the following is a full, clear, and exact description of the same.

The invention relates to improvements in molding machines, as set forth in the following specification and illustrated by the accompanying drawings that form part of the same.

The invention consists essentially of a frame, a plate or pallet covering in said frame and forming the bottom of the mold and having an opening therethrough, a core rigidly secured to said frame and rising through said opening, and a mold frame closing down on said plate and forming the sides of the mold.

The object of the invention is to simplify the method of producing drain tiles and to devise a convenient and reliable machine whereby one operation of the molding may be instantly followed by a second operation, and thus cheapen the cost of manufacture.

In the drawings Figure 1 is a perspective view of the invention showing one of the cores in cross section, and a portion of the plate or pallet cut away, and the mold frame in its open position. Fig. 2 is a perspective view of the machine in readiness to have the material to be molded placed therein. Fig. 3 is a longitudinal sectional view. Fig. 4 is an elevation of the machine from one end. Fig. 5 is a cross sectional view of the machine through one of the cores.

Like letters of reference indicate corresponding parts in each figure.

Referring to the drawings, *a* are the ends of the frame of the machine standing on the feet *b*, and preferably formed of metal having the flange *c* extending around the edges thereof except on the top sides, and the bolt holes *d* in pairs through the web portion and in proximity to the top sides thereof.

e are the sides of the frame having the in-turned flanges *f* at the ends thereof and suitable bolt holes through said flanges registering with the bolt holes *d* when the sides *e* are placed in position to be secured to the ends *a*.

g are bolts inserted through the bolt holes *d* and the bolt holes in the flanges *f* and

secured by the nuts *h*, thus firmly securing 55 the sides and ends together and forming a steady and rigid frame for the machine.

i are slots arranged at regular intervals in the top edges of the sides *e*, and *j* are holes arranged at regular intervals through the 60 sides *e* towards the upper edges thereof and midway between the slots *i*.

k is a plate or pallet supported on the frame of the machine and extending slightly beyond said frame, the sides and ends of said 65 plate having the longitudinally and downwardly depending flanges *l* towards the outer edges thereof, and the lateral flanges *m* depending downwardly from the underside of the plate and arranged at regular intervals 70 throughout the length thereof and forming part with the side flanges *l*.

n are openings through the plate *k* of rectangular shape and extending from side to side of said plate between the flanges *l* and 75 midway between each pair of flanges *m*. The plate or pallet *k* rests upon the upper edges of the frame formed by the ends *a* and sides *e* with the flanges *l* to the outside of the said frame and the lateral flanges *m* resting loosely 80 within the slots *i*.

o are cores preferably hollow and having the closed in ends *p* and the lugs *q* extending downwardly from said ends through which are the holes *r*. The cores *o* are shown as 85 semi-circular in cross section, though it must be understood that any desired shape in cross section may be used. The said cores are arranged to fit just within the openings *n* both at the sides and the ends and rest upon 90 the upper edges of the sides *e* of the frame, the lugs *q* extending downwardly through the said openings *n* and over the outer faces of the sides *e*, the holes *r* registering with the holes *j* in the said sides. *s* are screws inserted through the holes *r* and *j* and suitably 95 countersunk in the lugs *q* and holding said cores securely in position on the sides *e*.

t are brackets forming part with the ends *a* of the frame and extending upwardly and 100 rearwardly therefrom and having circular bosses *u* formed thereon and circular horizontal orifices *v* through the center thereof.

w is a rod inserted through the orifices *v* in the bosses *u* and extending beyond the said 105 bosses at each end of the machine.

x is a mold frame having the brackets *y* extending rearwardly from each end thereof,

each of the said brackets having a circular boss formed at the outer end thereof and a central orifice *z* forming a journal bearing into which extends projecting ends of the rod *w*, the inner faces of said brackets *y* abutting the outer surface of the bosses *u*. The mold frame is thus hingedly connected to the frame of the machine.

2 are cotter pins inserted through suitable 10 holes in the rod *w* immediately adjoining the inner surface of the bosses *u*, thus holding the said rod securely in position and preventing the mold frame *x* from being displaced.

The mold frame *x* is formed of the front 15 and rear sides 3 and 4 respectively, longitudinally arranged with the machine and the end pieces 5 preferably forming part with the rear side 4 and extending laterally therefrom and abutting the front side 3 and the 20 cross pieces 6 extending between said sides and preferably forming part with the rear side and arranged at equal distances apart so that when the mold frame *x* is swung downwardly on to the plate *k*, the said cross 25 pieces 6 will come into close contact with the said plate *k* in between the cores *o*, and the end pieces 5 will come into contact with the plate *k* in proximity to the outer cores *o* thus forming a plurality of boxes or molds for 30 molding purposes. The cross and end pieces of the mold frame *x* are formed V-shaped in cross section, the point of the V coming into contact with the plate *k* and the larger portion of the said cross and end 35 pieces being level with the upper edges of the sides 3 and 4. This particular formation of the cross and end pieces forming the molds is not essential to the invention as they may be made in any desired shape according to 40 the design of tile required. The front side 3 of the mold frame is in a separate piece and secured by the bolts 7 to two of the cross pieces 6 and so arranged that it may be pulled outwardly away from the ends of said 45 cross pieces to a limited extent, for otherwise in the swinging of the said frame on its hinges, the said side piece 3 would interfere with the material filling the molds. The heads of the bolts 7 do not come into direct 50 contact with the outer surface of the said side 3 when the latter is abutting the cross pieces 6 and the ends 5, and therefore the said side 3 may be pulled outwardly, sliding on the shanks of the bolts 7 and in order to 55 facilitate the handling of the said side 3 and mold frame handles 8 are provided extending therefrom at each end and preferably forming part therewith.

9 are locking arms for securely holding the 60 side 3 tightly abutting the ends and cross pieces of the mold frame. The arms 9 are pivotally secured to the side 3 by suitable bolts 10 and have a vertical slot 11 from the under edge thereof, the edges of the 65 said slot being beveled from the top portion

to the lower edge of the arm. The outer ends of the arms 9 are turned outwardly forming handles 12 to facilitate their operation. The arms 9 are pivoted so as to swing inwardly and bring the mouth of the 70 slots 11 in alinement with the shanks of the bolts 7, consequently when the mold frame is in its downward position and in contact with the plate *k*, the said arms 9 when in engagement with said bolts force the side 3 75 tightly against the cross pieces 6 and end pieces 5, the beveled edges of the slots acting as a wedge and pushing against the heads of the bolts.

In order to lift the mold frame, the arms 9 80 are released from engagement with the bolts and the side 3 pulled outwardly on the shank of the bolts as explained.

13 are lugs extending from the rear of the end pieces *a* and forming a support for the 85 mold frame *x* for preventing its further backward movement, and 14 are lugs from the said mold frame *x* which come into contact with the lugs 13 on the opening up of the 90 said frame.

15 is a bracket securely bolted by the bolts 16 to the rear portion of one of the end pieces *a*.

17 is the upper arm of the bracket 15 and 18 the lower arm, said arms having the orifices 19 and 20 respectively therethrough at the outer ends thereof, and the upper arm having its laterally extending portion, in which the said orifice 19 is arranged, on the same level as the upper surface of the mold 100 frame *x*.

21 is an elbowed rod supported by the bracket 15 and having the vertical section thereof inserted through the orifices 19 and 20 in the arms of the said bracket 15, and the 105 horizontal section extending across one end of said machine when in its closed position, from above the upper arm 17.

22 is an open frame having its longitudinal pieces 23 and 24 extending beyond the frame 110 portion of the machine, said longitudinal pieces having the orifices 25 therethrough, through which the horizontal section of the elbowed rod 21 is inserted. The frame 22 is securely held in place on the rod 21 by the 115 cotter pins 26 and washers 27 on either side of the outer arm 23. The longitudinal piece 24 extends beyond the rod 21 and terminates in the shoe 28 which in the vertical open position of the frame 22 engages the vertical 120 section of the elbowed rod 21 and supports said frame in a leaning position clear of the mold frame *x* when in its raised position. At the other end of the frame 22 a handle 29 is securely attached, while intermediate of the 125 length of the longitudinal piece 23 a guide plate or block 30 is secured to the outer side, which in the closed position of the frame abuts the outer surface of the side 3 of the mold bar *x*. The frame 22 thus forms 130

around the mold frame, a combing or hopper to hold the loose material which is to be packed into the molds from falling away from the edges of the said molds.

- 5 In assembling the parts of the machine for the purpose of molding, the cores *o* are set in position and secured as explained, to the sides *e*. The plate *k* is then placed over the said cores *o* the under surface resting on the top edges of the ends *a* and sides *e*, the cores *o* passing through the openings *n* in the said plate. The complete half cylinders formed by the cores *o* now extend through the openings *n*, the sides of said openings abutting the 15 surfaces of the said cores and forming a tight bottom through which no material can pass. The mold frame *x* is then swung upon its hinges to its downward position and the arms *q* locked on the bolts 7 as explained, 20 forcing the side 3 tightly up to the ends of the end and cross pieces 5 and 6 respectively and against the closed ends of the cores *o*, the other side 4 being also close to and abutting the other ends of the cores *o*. The frame 22 25 is then swung inwardly on its pivot towards the end *a* and then let down above the mold frame *x* forming a combing as already explained. It will be thus seen that there are a plurality of mold boxes in readiness for filling 30 with the material of which the tiles are to be made, the combing formed by the frame 21 permitting the filling in of more material than is actually required to fill the molds. Subsequent to filling in the molds with the material, the said material is tamped with a suitable tamping instrument and packed very tightly in the said molds and when it has been tamped sufficiently the frame 22 is 35 swung, on its pivot, outwardly over the top surface of the mold frame *x* thus scraping off all surplus material from the top of the said molds.

The use of the frame 22 is most advantageous as it serves the purpose of a hopper 40 to facilitate the proper filling of the molds and also cleans off all surplus material from the top surface of the molds leaving an even finished surface to the material in the molds.

The double hinge action permissible in the 45 use of the frame 22, allows it to swing freely in a horizontal direction and also allows it to be moved vertically so that it can be lifted clear of the mold frame at any point and when the tops of the molds are properly finished off may be swung clear of the machine to permit the removal of the mold frame *x*.

In removing the mold frame the locking arms 9 are released and the side 3 pulled outwardly as described, the frame *x* may then 50 be swung upwardly on its hinges clear of the material included the front plate 3 clearing the upper edges of same. The plate *k* may then be removed with the half tiles formed thereon leaving the cores *o* still secured to the frame 55 of the machine and in order to hasten the

work, spare plates *k* may be used and the molding continued, using the same cores and the same frame.

In the drawings and foregoing specification a machine for forming half tiles has been 70 described and it must be understood that while the surface of the plate *k* is shown smooth, suitable ribs or projections may be arranged thereon for indenting the edges of the half tile, or depressions may be made in 75 the said plate to form ribs or ridges upon the edges of the half tile, as may be desired so that when the half tiles are laid together they will have inversely, projecting ribs and depressions on the meeting edges to lock 80 them securely together.

It must also be understood that without departing from the spirit of the invention a mold plate forming the bottom half of a complete tile may be laid upon the frame in 85 a similar manner to the plate *k* and the cores set in the same in any suitable manner instead of being secured to the frame so that when the mold frame is swung into its downward position a mold for forming a complete 90 tile would be formed.

The cores herein described and shown are attached to the side bars, but it must be understood, that, without departing from the spirit of my invention, said cores may be attached to a separate bar or frame adjustably arranged within the machine frame so that in the operation of the machine the cores may be dropped away from the pallet or plate if desired. Further, the construction 95 of the frame may be to some extent altered, as the ends may be rigidly held together independent of the sides of the frame, and the said sides may be arranged to fit into prepared slots in the ends of the frame. 100

What I claim as my invention is:—

1. In a molding machine, the combination with an open frame, of a plate or pallet resting on and covering in said frame and forming the bottom of the mold and having an 110 opening therethrough, a core rigidly secured to and supported from said frame and rising through said opening in said pallet, and a mold frame closing down on said pallet and forming the sides of the mold around said 115 core and having a separable outer side adapted to be moved laterally, substantially as and for the purpose specified.

2. In a molding machine, the combination with the frame, of a plate or pallet supported from said frame and forming the bottom of the molds and having a plurality of openings therethrough, a plurality of cores rigidly secured to said frame and rising through the 120 openings in said plate, and a mold frame 125 hingedly secured to the aforesaid frame and closing down on said plate and having a plurality of laterally arranged divisions and a separable outer side secured thereto, and adapted to be moved laterally therefrom to 130

clear the ends of said cores as and for the purpose specified.

3. In a molding machine, the combination with a frame, of a plate or pallet resting upon the edges of said frame and forming the bottom of the molds and having reinforcing flanges from the underside thereof and a plurality of rectangular openings therethrough, a plurality of cores extending across said frame and rigidly secured thereto and rising through the openings in said plate, a mold frame hingedly secured to said frame and having a plurality of lateral divisions contacting with said plate in the closed position of said frame and a separable outer side secured to said divisions and abutting the outer ends thereof and adapted to be moved outwardly from the ends of said divisions, and means for holding said outer side closely abutting said arms and for releasing the said side, as and for the purpose specified.

4. In a molding machine, the combination with a frame, of a plate or pallet resting upon the edges of said frame and forming the bottom of the molds and having reinforcing flanges from the underside thereof and a plurality of rectangular openings therethrough, a plurality of cores extending across said frame and rigidly secured thereto and rising through the openings in said plate, a mold frame hingedly secured to said frame and having a plurality of lateral divisions contacting with said plate in the closed position of said frame and a separable outer side adapted to be moved outwardly from the ends of said divisions and having orifices therethrough, bolts secured to said mold frame and extending through the orifices in said separable side and having their heads to the outside thereof, and arms pivotally secured to said separable side having slots engaging the shanks and inner surface of the head of the said bolts and holding said separable side closely abutting the ends of the lateral divisions of said mold frame, as and for the purpose specified.

5. In a molding machine, the combination with a frame having separable sides and ends rigidly secured together said ends having rearwardly projecting brackets therefrom, of a plate or pallet resting upon the edges of said frame and forming the bottom of the molds and having longitudinal reinforcing flanges from the underside toward the edges and a plurality of lateral flanges from the underside joining said longitudinal flanges at intervals throughout the length thereof and a plurality of rectangular openings between said lateral flanges through said plate, a plurality of cores extending across said frame and rigidly secured to the sides thereof and rising upwardly therefrom through said openings and registering therewith, a mold frame having rearwardly projecting lugs therefrom

registering with the brackets on the ends of the frame and hingedly connected therewith and a plurality of divisions contacting with the aforesaid plate in the closed position of said frame and a separable outer side secured to the outer ends of said divisions by suitable bolts adapted to be moved outwardly said bolts having shanks projecting outwardly through said side, arms pivotally secured to said separable side and having slots engaging the shanks and inner surface of the heads of said bolts and forcing said side inwardly to the end of said divisions, as and for the purpose specified.

6. In a molding machine, the combination with the frame, of a plate or pallet covering in said frame and forming the bottom of the mold and having an opening therethrough, a core rigidly secured to said frame and rising through said opening, a mold frame closing down on said plate and forming the sides of the mold around said core, and an open frame resting on the upper side of said mold frame and pivotally supported from the aforesaid frame, as and for the purpose specified.

7. In a device of the class described, in combination, a frame, a mold supported thereby, a bracket fixedly secured to one end of said frame, and an open frame resting on the upper side of said mold and pivotally supported from said bracket and adapted to be swung horizontally or vertically, substantially as described.

8. In a device of the class described, in combination, a frame, a mold supported thereby, a bracket secured to one end of said frame having an orifice in the upper arm and an orifice in the lower arm thereof, an elbowed arm turning in the orifices in the arms of said bracket and supported thereby, and an open frame having two of its sides extending beyond the frame portion and pivoted on the horizontal portion of said elbowed arm and one of said extending sides extending beyond said pivot point and having a shoe formed thereof to engage the vertical section of said elbowed arm when the said frame is in a vertical position said frame being suitably secured on said elbowed arm and adapted to swing in horizontal and upward and outward direction to and from and across said mold frame, as and for the purpose specified.

9. In a molding machine, the combination with the frame, of a plate or pallet covering in said frame and forming the bottom of the mold and having an opening therethrough, a core rigidly secured to said frame and rising through said opening, a mold frame closing down on said plate and forming the sides of the mold around said core, a bracket secured to one end of the aforesaid frame having an orifice in the upper arm and an orifice in the lower arm thereof, an elbowed arm turning in the orifices in the arm of said bracket and supported thereby, and an open frame hav-

ing two of its sides extending beyond the frame portion and pivoted on the horizontal portion of said elbowed arm and one of said extending sides extending beyond said pivot 5 point and having a shoe formed thereon to engage the vertical section of said elbowed arm when the said frame is in a vertical position, said frame being pivoted on said elbowed arm and adapted to swing in a horizontal and upward and outward direction to and from and across said mold frame, as and for the purpose specified.

10. In a molding machine, the combination with a frame having separable sides and ends rigidly secured together said ends having rearwardly projecting brackets therefrom, of a plate or pallet resting upon the edges of said frame and forming the bottom of the mold and having longitudinal reinforcing flanges 15 from the under side towards the edges and a plurality of lateral flanges from the under side joining said longitudinal flanges at intervals throughout the length thereof and a plurality of rectangular openings between said 20 lateral flanges through said frame, a plurality of cores extending across said frame and rigidly secured to the sides thereof and rising upwardly therefrom through said opening and

registering therewith, a mold frame having rearwardly projecting lugs therefrom registering with the brackets on the ends of the frame and hingedly connected therewith and a plurality of divisions contacting with the aforesaid plate in the closed position of said frame and a separable outer side secured to the outer ends of said divisions by suitable bolts, and adapted to be moved outwardly from said divisions said bolts having shanks projecting outwardly through said side, arms pivotally secured to said separable side and 30 having slots engaging the shanks and inner surface of the heads of said bolts and forcing said side inwardly to the ends of said division, and an open frame resting on the upper side of said mold box and pivotally supported 35 from the aforesaid frame, as and for the purpose specified.

Signed at the city of London, county of Middlesex, in the Province of Ontario, Dominion of Canada, this 3rd day of October, 1906.

HENRY POCOCK.
